FREQUENCY MODULATION SIGNAL RECEIVING SYSTEM

George L. Beers, Haddonfield, N. J., assignor to
Radio Corporation of America, a corporation
of Delaware

Application February 12, 1942, Serial No. 430,588

33 Claims. (Cl. 250—20)

This invention relates to frequency modulation signal receiving systems of the type in which frequency variations of the carrier wave or mean frequency of the signal are employed for the reproduction of transmitted signals.

An important object of the invention is to provide an improved receiving system of the character referred to which achieves improved noise reduction, particularly in response to weak signals, and improved adjacent channel selectivity.

It is a further object of the invention to provide an improved frequency modulation signal receiving system in which the frequency variation or swing corresponding to a predetermined percentage modulation of the received signal is reduced prior to demodulation and reproduction of the signals. In the particular embodiment of the invention which will be described herein, demodulation is effected by a discriminator-rectifier network which converts frequency variations into amplitude variations prior to detection.

Another object of my invention is to provide an improved frequency modulation signal receiving system in which the frequency deviation of the received signal is reduced by a predetermined ratio, such as 5 to 1, before demodulation.

It is also a further object of the present invention to provide novel means for preventing interfering frequencies which would operate over a frequency variation range extending outside of the useful portion of the discriminator characteristic from reaching the discriminator network.

Another object of the invention is to provide an improved frequency modulation signal receiving system including a circuit inherently responsive to frequency variations in a received signal over a restricted range, and means for automatically causing said circuit to accept variations in the frequency of the received signal over a wider range of frequencies.

A receiving system in accordance with the present invention may include means for heterodyning a received frequency modulated carrier wave, or signal, to produce a corresponding intermediate frequency wave modulated over a range of frequencies. The latter is applied to an oscillator which is locked in with the frequency modulated wave over a range of frequency variations including, and substantially limited to, the range of frequencies of the modulated wave. The output of the oscillator is fed to the discriminator network.

The locked-in oscillator is important in carrying out the objects of improved noise reduction and improved adjacent channel selectivity. The 55

only signal which reaches the discriminator is that represented by the frequency variations of the locked-in oscillator. By designing the oscillator so as to lock in only over a frequency swing substantially limited to the range of frequencies of the desired modulated wave, the oscillator is prevented from shifting its frequency sufficiently to lock in with interfering frequencies outside of such range or with an undesired signal on an adjacent channel.

In accordance with other objects hereinbefore stated, the locked-in oscillator produces voltages at sub-harmonics or sub-multiples of the frequencies of the intermediate or other supplied modulated wave, and the oscillator is coupled to selective circuits in the discriminator network which are responsive to the band of sub-multiple frequencies produced by the oscillator. The signal applied to the locked-in oscillator may, in one embodiment of the invention, shift the oscillator frequency only the equivalent of a small percentage modulation, such as from 20 to 35 percent. It is, therefore, a further object of my invention to provide an improved frequency modulation receiving system in which a dynamic frequency control is provided in connection with the modulation, sufficient to lock in the oscillator for signals over a frequency range corresponding to a predetermined maximum percentage modulation.

It is a further object of the present invention to provide control of the locked-in oscillator frequency through a reactance control tube, or other suitable frequency control means, directly responsive to modulation frequency potentials at the output of the discriminator. The coupling network between the discriminator and the reactance tube is designed to pass only the desired modulation frequencies. Since the oscillator without the control obtained from the reactance tube will lock in with a received signal for only a relatively small frequency swing, that is, over a restricted range only, and since frequencies outside the modulation frequency band are not fed back from the discriminator output to the reactance tube and therefore do not control the oscillator frequency, the frequency shift of the oscillator which the reactance tube can produce is limited to the useful modulation range. The oscillator will not follow beyond its restricted lock-in range frequencies, even though they are within the range of useful frequencies impressed on the oscillator, which if demodulated would produce superaudible output potentials. More-

over, the reactance control tube cannot shift the oscillator frequency so that it will lock in with the signal on an adjacent channel because the circuit elements are so designed that if the frequency of the oscillator were to change beyond the useful range of the discriminator and towards the adjacent channel, the phase and magnitude of the potential applied from the demodulator to the reactance tube would shift in such a manner that the effect of the reactance tube on the oscillator would be to reverse the direction of the oscillator frequency change so that its frequency would nevertheless stay within the limits of the desired channel. This frequency swing limitation is also effective to minimize noise.

One of the major problems in the design of frequency modulation receivers is to obtain adequate sensitivity with stability. The sensitivity or voltage gain which can be obtained at a given frequency without resorting to special precautions which materially increase manufacturing costs is limited. This difficulty is diminished if the gain is obtained at two different frequencies, as in the superheterodyne receiver. However, in some frequency modulation receivers of conventional design it has been found necessary to resort to a double heterodyne type of superheterodyne receiver in which two successive intermediate frequencies are used in order to obtain the desired sensitivity and stability. The double heterodyne type of superheterodyne has the disadvantage that strong signals from local transmitters produce additional spurious responses which frequently interfere with the reception of weaker signals.

It is, accordingly, another important object of my invention to provide a frequency modulation receiver in which satisfactory sensitivity is obtained with a high degree of stability.

It is likewise another object of the invention to obtain the desired voltage gain between the antenna and discriminator in a frequency modulation receiver at three different successive frequencies without encountering the complications, or disadvantages, of the double heterodyne type of superheterodyne receiver.

Wherever the term frequency modulation is used throughout the specification and claims, it should be understood to refer to any modulation wherein the instantaneous frequency of the transmitted waves is varied by the application of modulating voltage of an alternating character such as music or speech. There are many possible functional relations between the instantaneous wave frequency and the modulating voltage, which are or can be used. For example, if the instantaneous frequency is caused to shift in direct proportion to the instantaneous value of the modulating voltage, there results one common form of frequency modulation, or if the instantaneous frequency is caused to vary as the time integral of the modulating voltage there results a type of frequency variation, which is usually called phase modulation because it is with equal correctness, and somewhat more simply, definable as a modulation which causes the phase of the transmitted waves to shift in direct proportion to the instantaneous value of the modulating voltage. In other words, the terms "phase modulation" and "frequency modulation" are tied together by the fact that a changing frequency necessitates a changing phase and vice versa. Furthermore, in many practical systems going under the name of frequency modulation (FM), the instantaneous frequency does not vary

directly as the voltage of the modulating voltage, nor yet as its integral, but in some intermediate fashion. Regardless of the exact nature of the functional relation mentioned above, however, the system of the present invention can be employed and hence such terms as "frequency modulation," "frequency modulated," and the like should be taken in the broad sense here defined.

The novel features which I believe to be characteristic of my invention are set forth with particularity in the appended claims. The invention both as to its organization and method of operation will best be understood by reference to the following illustrative description taken in connection with the drawings in which I have indicated diagrammatically several circuit organizations whereby my invention may be carried into effect.

In the drawings:

Fig. 1 is a schematic circuit diagram which illustrates one form of a frequency modulation signal receiving system embodying the invention.

Fig. 2 is a schematic circuit diagram illustrating another form of frequency modulation receiving system incorporating my invention and providing certain performance advantages over the system shown in Fig. 1.

Figs. 3 and 4 are graphs illustrating certain operating characteristics of the circuit of Fig. 2, and

Fig. 5 depicts additional control means for the reactance tube employed in one embodiment of my invention.

Referring to the accompanying drawings, wherein like reference characters in the different figures designate similar circuit elements, the signal input circuits of my receiving system may be of any suitable type. To simplify the drawings, block diagrams are employed to represent the radio frequency amplifier 5, first detector 6, local oscillator 7, and intermediate frequency (I. F.) amplifier 8 of the usual superheterodyne type of vacuum tube receiver circuit. A conventional dipole antenna is indicated at 9 as a suitable collector of signals for the radio frequency amplifier 5.

The intermediate frequency amplifier 8 is provided with an output transformer 10 having primary and secondary circuits resonant to the intermediate frequency. As illustrated, the primary and secondary circuits of transformer 10 are suitably coupled and a variable resistor 11' is connected in shunt with the secondary receiving circuit 11 to give the transformer a resonance curve of the desired breadth. In the present example, the intermediate frequency may be assumed to be 4.3 mc. (megacycles), and the transformer 10 is designed to pass the frequency band occupied by the modulated carrier wave with 100% modulation. For the frequency modulation broadcasting standards in use at the present time, the input circuits of the receiving system, including the intermediate frequency transformer 10 with its secondary circuit 11, are constructed to receive a carrier wave with a total frequency swing of the order of 150 kc. (kilocycles).

It will be understood by those skilled in the art that the devices 5, 6, and 7 are provided with the usual variable tuning means. The input circuits of amplifier 5 and first detector 6 are each tuned to the mean or center frequency of the desired station channel, while the oscillator 7 is tuned to an oscillation frequency differing from said mean frequency by the value of the desired

intermediate frequency. The present frequency modulation (FM) band is 42 to 50 mc., with each transmitter station allotted a channel width of 200 kc.

The output circuit 11 is followed by a vacuum tube oscillator 12, which includes a tuned tank circuit 13, and a suitable frequency selective network, or discriminator, which as shown comprises tuned circuits 14 and 15 by which the applied signal is converted to amplitude modulation. The signal is detected by suitable rectifiers 16 and 17 coupled to said circuits 14 and 15 which are preferably shunted by resistors 14' and 15' respectively for reasons which will be hereinafter set forth. The usual rectifier output impedance, or resistor, is indicated at 18. An output circuit 19 is connected thereto, one side of the output circuit being grounded as indicated at 20. The audio frequency, or modulation, output connection lead 21 is coupled to the circuit 19 through a suitable capacitor 22.

The invention in its broader aspects and as set forth in some of the appended claims may be employed with a locked-in oscillator operating at the same frequencies as the modulated intermediate frequency wave. In its preferred embodiments, however, the oscillator 12 which immediately precedes the discriminator network produces voltages of frequencies less than the intermediate frequency and having a frequency swing less than that of the intermediate frequency wave. The oscillator tube envelope contains a grid 35 connected to the intermediate frequency secondary circuit 11 which in turn is connected to ground through a by-pass condenser 12'. In the present example, the tank circuit 13 connected to the anode 40 of oscillator 12 comprises a variable magnetic core inductance 31 and a shunt tuning capacitor 32, and is tuned to a sub-multiple frequency of the intermediate frequency signal applied to the grid 35 to cause the tube 12 to produce oscillations of such sub-multiple frequency.

The circuit 13 is grounded at 29 through a by-pass condenser 30 and is caused to oscillate at the predetermined sub-multiple frequency by feedback through inductive couplings between the inductance 31 and an inductance indicated at 42. The latter has a shunt tuning capacitor 43 included in a circuit 47 which is preferably shunted by a resistor 47' and is connected between a second control grid 44 and ground, or cathode, through a suitable grid resistor 45 shunted by a grid capacitor 46. The normal oscillator frequency is primarily determined by the tuning of circuit 13. The tube 12 may be a pentagrid tube of the 6SA7 type, and is preferably locked-in by the impression of the 4.3 mc. signal on the first grid of the tube, which is the grid 35 in the present example. The cathode 36 of tube 12 is grounded at 37. Screen grids 36' and a suppressor grid 37'' are arranged as shown on the drawings.

In the oscillation circuits above described, the circuit 47, comprising winding 42 and condenser 43, has a natural frequency of resonance higher than that of circuit 13. In a successful embodiment of the invention, the inductance 42 of circuit 47 was between one-fifth and one-sixth of the inductance of winding 31, and the capacity of condenser 43 was approximately 100 mmf. (micromicrofarads), whereas condenser 32 had a capacity of approximately 35 mmf.

Coupling connection between the locked-in 75

oscillator 12 and the discriminator network is provided through a circuit lead 26, a resistor 25, and a variable coupling capacitor 27 connected to the anode 40 of the oscillator and to the high potential sides of circuits 14 and 15. Since the oscillator applies its output voltage to the discriminator whether a signal is being received or not, and since both the frequency and the frequency swing of the voltages which it produces are different from the intermediate frequency signal which is applied to the grid 35, it is apparent that the radio frequency signal waves collected at the signal collector device, such as the usual antenna, do not themselves pass through the receiving system to the discriminator, but operate to control the frequencies of the voltages produced by the oscillator.

It is common practice to include limiter means in a conventional frequency modulation receiving system, for limiting the amplitude variations resulting from noise impulses or other causes. By proper choice of the circuit constants of the oscillator 12 and in particular of the coupling between the circuits 13 and 47 and the operating potentials applied to the tube electrodes, the oscillator voltage applied to the discriminator can be made substantially independent of the strength of the intermediate frequency signal.

Grid current on grid 35 may be employed in place of the usual separate diode for automatic volume control (AVC) of the preceding tubes 5, 6, and 8. Through a tap connection on the series resistor elements 38-39 (if desired resistor 38 may be omitted), the AVC lead 62 is connected to ground 37'. The other end of lead 62 is connected to grid control circuits 63 through a suitable filter network 64. Those skilled in the art are fully acquainted with this manner of effecting gain control. If the carrier amplitude increases above the desired level the negative voltage fed over the lead 62 to the control grids of the controlled tubes increases, acting to decrease the gain of the tubes and to prevent them from being overloaded. A diode and appropriate load resistor, connected in shunt with the primary circuit of the transformer 10 or at some other suitable point in the receiver system, could be used to provide the AVC potential in conventional manner.

Since the locked-in oscillator 12 operates at a submultiple of the instantaneous frequency of the modulated carrier impressed on grid 35, frequency division is obtained in which not only the mean-carrier frequency is reduced, but also the frequency swing is correspondingly reduced. In the present example with an intermediate frequency of 4.3 mc. supplied by the circuit 11, the circuits 13, 14 and 15 may be made responsive to a mean sub-multiple frequency of 860 kc. thereby providing at 5:1 frequency reduction and a corresponding reduction in the frequency swing. For example, if at any instant, the received signal has been heterodyned to an intermediate frequency of 4.375 mc. (up 75 kc. from the mean or center frequency of 4.3 mc.) the frequency of the locked-in oscillator will then be 875 kc. (up 15 kc. from the mean sub-multiple frequency of 860 kc.), preserving the 5:1 ratio with the intermediate frequency on grid 35. Thus there occurs in the circuits 13, 14 and 15 a frequency deviation from the mean frequency of ± 15 kc. for full modulation, assuming that the applied signal has a maximum frequency deviation of ± 75

kc. The maximum frequency swing of the signal applied to the discriminator is thus limited in this example to an audio frequency of 15 kc. on each side of the mean frequency.

The discriminator network may be of any suitable type for converting a frequency modulated signal into an amplitude modulated signal for detection by the rectifiers 16 and 17. As shown, it comprises a selective system of the type more fully described in the application of John D. Reid, Serial No. 353,028, filed August 17, 1940, and includes tuned parallel-resonant circuit 15 comprising inductance and capacity connected between the anode of rectifier 16 and that of rectifier 17. The capacity existing across the electrodes of rectifier 17 is indicated in broken lines by capacity 15' and provides in combination with circuit 15 a series circuit tuned to resonance at the lower frequency end of the admittance band of the discriminator which in this example of the invention is somewhat below 845 kc., while the parallel-resonant circuit 15 resonates at the higher frequency of the discriminator admittance band, i. e., somewhat above 875 kc. This frequency selective network provides a linear operating characteristic for a frequency swing of ± 15 kc., as will be more fully described below.

Each of the coils of transformer 10 and the coils of circuits 14 and 15 may have adjustable cores composed of powdered magnetic material. A single core of such material may be used with coils 31 and 42. The coil 14 need not be inductively coupled either to the oscillator circuits 13 or 41 or to the discriminator circuit 15.

The description of the invention, as thus far given, applies to the forms shown in both Figs. 1 and 2 and refers to elements which are denoted by similar reference characters on such figures. In each case, the discriminator circuits associated with the rectifiers 16 and 17 are similar to those described in the application of John D. Reid, Serial No. 353,028, filed August 17, 1940, to which reference is made for a more detailed description of construction and manner of operation.

In the discriminator circuit shown in Fig. 1, the end of circuit 14 remote from condenser 27 is connected to a midtap on the resistor 18 in the output of rectifiers 16 and 17. A high frequency by-pass condenser 68 is connected across the upper half of resistor 18 and to the cathode of rectifier 16, and a similar condenser 67 is connected across the lower half of resistor 18 and to the cathode of rectifier 17. The upper ends of circuits 14 and 15 are conductively connected together both for alternating and direct currents. The capacity between anode and cathode of rectifier 17 is represented by condenser 15' shown in broken lines. As more fully described in the said Reid application, Serial No. 353,028, the circuit 15 in combination with capacity 15', is series resonant to the lowest frequency of the admittance band of the discriminator, and the circuit 15 per se is parallel-resonant to the highest frequency of such admittance band.

The above circuits provide a direct current path from circuit 14 to the mid-tap on resistor 18, which is completed through the upper half of resistor 18, and rectifier 16 back to circuit 14 and a second direct current path which is completed through the lower half of resistor 18, rectifier 17, circuit 15, and circuit 14 back to the mid-tap on resistor 18. It will be noted that direct current in the first-mentioned path including rectifier 16 tends to make the upper end of resistor 18 posi-

tive with respect to ground, and that current through the second direct current path including rectifier 17 tends to make the upper end of resistor 18 negative to ground.

5 The circuit 14 functions mainly as a tuned circuit resonant in the example of the operation of the invention described herein to approximately 860 kc. and interposed between the output of the locked-in oscillator 12 and the input to the discriminator-rectifier. Its lower end is effectively grounded at 20 through the high frequency bypass condenser 67. The circuit 14, however, acts as part of the discriminator-rectifier in that it provides a direct current path from the midpoint 15 of resistor 18 to the anode 16 of the upper diode. Such a D.-C. path may, of course, readily be provided in other ways as appears from the above-mentioned Reid application and as will further appear below in the description of Fig. 2.

20 If an unmodulated carrier is received, it produces an intermediate frequency of 4.3 mc., and the oscillator 12 produces a sub-multiple frequency of 860 kc. The impression of a frequency of 860 kc. on the discriminator causes equal currents to flow in the upper and lower halves of resistor 18. Inasmuch as such currents flow in opposite directions, they do not affect the potential of the upper end of resistor 18 with respect to ground. If, however, a modulated signal causes a frequency higher than 860 kc. to be impressed on the discriminator, there results greater current flow through rectifier 16 than through rectifier 17, causing the upper end of resistor 18 to have a positive potential of a value depending upon the difference in current flow in the respective rectifier paths, whereas when frequency modulation causes a frequency lower than 860 kc. to be impressed on the discriminator, there results greater current flow through rectifier 17 than through the other direct current path. This impresses a negative potential at the upper end of resistor 18, again dependent upon the difference in the flow of current in the respective direct current paths.

45 It is necessary in a receiver as shown in Fig. 1 that the oscillator 12 be locked in with the intermediate frequency wave impressed on grid 35 over the range of 100% modulation. It has been found, however, that by restricting the lock-in 50 range of the oscillator substantially to that required for 100% modulation, i. e., the useful portion of the discriminator characteristic, the adjacent channel selectivity of the receiver can be materially increased. It is known that the higher 55 the

[inductance
capacity]

ratio of the oscillator circuit 13 the wider the 60 frequency range over which the oscillator will lock-in, and I have also found that the degree of coupling between the oscillator circuit 13 and the discriminator network 14, 15 is an important factor in controlling the width of the lock-in 65 range. In a successful embodiment of Fig. 1 the oscillator circuit 13 was coupled to the discriminator network through a resistance 25 of 5600 ohms and a condenser 21 of 8.2 mmf., which were 70 found to give suitable coupling for full modulation over a frequency swing of ± 15 kc. at the input to the discriminator. This degree of coupling may, of course, be increased by reducing the value of resistance 25 or increasing the capacity of condenser 21. With this arrangement,

an increase in the degree of coupling widens the lock-in range and a decrease, assuming that the

$$\frac{L}{C}$$

ratio of oscillator 13 remains the same, reduces the lock-in range.

It will be noted that Fig. 2 shows a discriminator-rectifier network somewhat different from that shown in Fig. 1. In Fig. 2, the low potential side of the circuit 14 is connected directly to ground, as at 28, instead of to the center tap on resistor 18 and the circuits 14 and 15 are coupled by condenser 80. The anode of diode 16 is connected to the center tap on resistor 18 to provide the D.-C. path which in Fig. 1 is completed through circuit 14, and a single high frequency by-pass condenser 81 is employed in place of the condensers 67 and 68 of Fig. 1. This results in an arrangement specifically described in the said application of John D. Reid, Serial No. 353,028, with particular reference to his Fig. 4. The specific discriminator-rectifier circuits shown in Figures 1 and 2 are not an essential part of the invention, and other circuits can be employed which will give satisfactory results. For example, a discriminator-rectifier of the type shown by S. W. Seeley in U. S. Patent No. 2,121,103, granted June 21, 1938, may be used. Again, a pair of opposed rectifiers with oppositely, and equally, mistuned input circuits as disclosed by Conrad in U. S. Patent No. 2,057,640, granted October 13, 1936, may be employed. Likewise the discriminator circuit shown in Figure 1 can be interchanged with that in Figure 2, and vice versa.

It may be noted that in all of Figs. 1, 2 and 4 of the Reid application, Serial No. 353,028, the direct current connection from the midpoint of the resistor corresponding to resistor 18 of this application goes to the anode of the lower diode, whereas in Fig. 1 of the present application the corresponding D.-C. lead goes through circuit 14 to the anode of the upper diode, and in Fig. 2 is directly connected to the anode of the upper diode. The connection to the anode of the upper diode rather than to that of the lower diode is, however, not a departure from the disclosure of the Reid application, since Reid pointed out that this D.-C. connection may be made with the anode of either of the rectifiers or to any point between them which provides a D.-C. path to the diode plates. With all of the connections shown in the Reid application and in this application, the high frequency potential at the anode of the upper diode is effective in producing rectified potential across the upper half of the output resistor 18, and the high frequency potential at the anode of the lower diode is effective in producing rectified potential across the lower half of the output resistor.

It has been stated in the description of Fig. 1 that when the coupling between the discriminator, i. e., frequency selective, circuits 14, 15 and the oscillator 12 is decreased from the value used in Fig. 1, the frequency deviation range over which the oscillator will lock-in is also decreased. In describing Fig. 2 we may assume that the circuits associated with the oscillator 12 provide a lesser degree of coupling between the oscillator and discriminator circuits than in Fig. 1 and in the absence of apparatus other than that included in Fig. 1 would lock in over a limited range only. This may conveniently be effected by employing a smaller condenser 21, a larger resist-

ance 25, or both, and the lock-in range may represent only a relatively small part, such as between 20 and 35 percent, of the modulation frequency range. In the present description of this invention we may assume, for convenience, that the intermediate frequency signals impressed on the grid 35 in Fig. 2 can cause a frequency shift of the voltage delivered from the oscillator 12 only of the order of ± 5 kc. from the oscillator frequency determined by the tuning of circuit 13 before the oscillator falls out of control of the potentials on such grid. This is of advantage in preventing the reproduction of noise and of undesired signals. Without further provision useful signals requiring an oscillator frequency swing wider than ± 5 kc. would not be properly reproduced. In order to cause the oscillator 12 to be controlled by wider variations in the frequency of a received signal up to 100% modulation, the oscillator is provided with automatic frequency control means as follows:

The circuit 13, which immediately precedes the discriminator, is associated with a reactance control tube indicated at 50. The latter has a screen grid 50', a suppressor grid 50'' and an anode 51 connected through a lead 60 to the high potential side of circuit 13 and through the inductance 31 of circuit 13 to the positive power supply lead 41. The control grid 52 of reactance tube 50 is connected through a control circuit lead 53, including the condenser 71 shunted by a switch 70, to a tap 54 adjustable over a potentiometer 55 connected across the circuit 19-20 and is coupled to the circuit 13 through a phase shifting network 56 comprising series resistors 57 and 57' and suitable quadrature capacitors 58 and 58'. Anode potential is prevented from reaching the grid 52 by a blocking capacitor 59 located between the phase shifter 56 and the lead 60. By the use of high resistances at 57 and 57' and condensers 58 and 58' of high capacitive reactance there is developed across condenser 58' a voltage of the frequency of circuit 13, which is in lagging phase quadrature with the oscillatory voltage across circuit 13. The quadrature voltage across 58' is applied to grid 52. The plate to cathode impedance of tube 50 is connected across the circuit 13, and the quadrature voltage on grid 52 causes the plate to cathode impedance of tube 50 to simulate an inductive reactance, as more specifically described in the application of Charles Travis, Serial No. 19,563, filed May 3, 1935.

As the frequency of the modulated signal applied to control grid 35 of locked-in oscillator 12 starts to shift by a small amount within the restricted lock-in range of the oscillator 12, the sub-multiple frequency of the oscillator 12 is changed as heretofore set forth. Such varied sub-multiple frequency is impressed upon the selective circuits of the discriminator, and a corresponding change in potential is developed across resistor 18. This action will not be described in detail here, being effected as described above in connection with the operation of the discriminator of Fig. 1 and also more particularly described in the said Reid application, Serial No. 353,028. The frequency swing on grid 35 is converted by network 14, 15, 16, 17 into variations in rectified voltage across resistor 18, and consequently across potentiometer 55 in parallel with it, the magnitude and direction of which are a function of the amount and direction of the frequency swing. This variable potential across potentiometer 55 is applied to the grid 52 of the

reactance tube 50 in the proper magnitude and phase to shift the tuning of the oscillator tank circuit 13 in the same direction as the frequency shift of the intermediate frequency signals on grid 35. Thus, the restricted lock-in range of the oscillator 12 is shifted back and forth so that it is always such as to permit the oscillator to lock in with the frequency of a desired modulated wave over a frequency swing corresponding to 100% modulation. Thus a system which is made very selective with respect to its response to interfering impulses is through the use of a reactance tube feedback system made fully responsive to the desired modulation. This operation may be effected either by combined audio frequency and direct current potentials from potentiometer 55, when switch 70 is closed, or by audio frequency potentials through condenser 71, when switch 70 is open.

The frequency reduction from the intermediate frequency to the sub-harmonic frequency is shown graphically in Fig. 3, to which attention is now directed along with Fig. 2. The upper part of Fig. 3 shows the intermediate frequency of 4.3 mc. with the limits of its full frequency swing separated by 150 kc. resulting from a frequency shift, or deviation, of ± 75 kc., and in comparison therewith the lower part of the figure shows the sub-multiple frequency of 860 kc. providing a frequency reduction in the ratio of 5:1 and a corresponding reduction in the frequency swing, or frequency deviation, to ± 15 kc.

The limited frequency "lock-in" range of the oscillator in following the frequency swing of the controlling intermediate frequency is also indicated in Fig. 3. The three, heavy vertical lines in the lower part of the figure represent frequencies to which the oscillator 12 may be adjusted by the reactances in or across circuit 13. In the present example, the oscillator may be adjusted to the frequency of 860 kc. indicated by the central vertical line, without reference to reactance tube 50. By the reactance shunted across circuit 13 by the tube 50, the oscillator 12 may be adjusted to a frequency of 15 kc. lower than the central frequency of 860 kc. as indicated by the vertical line at the left, to a frequency of 15 kc. above the central frequency as indicated by the vertical line at the right, or to any frequency intervening between said limits. The horizontal lines in Fig. 3 denoted ± 5 kc. show that at any frequency to which the oscillator may be tuned, it has a lock-in range, for example, of the order of ± 5 kc. under the immediate control of frequency swing on grid 35.

As previously stated, the phase and magnitude of the potential impressed from potentiometer 55 on the control grid 52 of the reactance tube 50 control its effect on the frequency of the tuned circuit 13. The amplitude of the control potential applied to the reactance tube is normally kept slightly below the value which would shift the oscillator to the correct frequency, assuming that the oscillator had no lock-in range. In other words, for 100 percent modulation the reactance tube shifts the oscillator frequency by slightly less than ± 15 kc., the discrepancy being compensated for by the oscillator lock-in action.

In the operation of my receiving system, interfering frequencies within the ± 75 kc. response range of the intermediate frequency transformer 10 may be impressed on the grid 35 of oscillator 12. If sub-multiples of these interfering frequencies are permitted to reach the demodulator,

they may beat with each other or with the desired carrier to produce superaudible noise impulses. In order to prevent such interfering frequencies from beating with a desired carrier wave, the distributed capacities and impedances of the elements in the discriminator rectifier circuit 14, 15, 16, 17, etc. and in the phase shifting network 56 are made such that superaudible noise impulses either are not fed back to the reactance tube 50 at all or are not fed back in such phase and amplitude as to permit the oscillator tube 12 to follow them. Accordingly, the oscillator will not follow beyond its restricted lock-in range frequencies, even though they are within the range of frequencies impressed on the grid 35, which if demodulated would produce superaudible output potentials, because the feedback connections between the discriminator-rectifier circuits and the reactance tube are designed to pass only the desired modulation frequencies, and the frequency shift of the oscillator which the reactance tube can produce is therefore limited to the useful modulation range. In other words, the receiving system is provided with a circuit which is responsive only to small frequency variations, and this restricted response range is moved back and forth at a rate which follows the desired modulation of received signals but is not moved back and forth at a rate which will follow superaudible noise impulses which may be present with the received signals. In this way, frequency swing limitation is provided for superaudible noise frequencies, such frequencies being prevented from combining with the carrier in the discriminator-rectifier system. This increases the ratio of the carrier energy to the combined energies of the side bands including the noise components.

The effect of the reactance tube circuit on adjacent channel selectivity is also of interest. This can best be understood by reference to Fig. 4 which shows the demodulator, i. e., discriminator-rectifier, voltage-frequency response characteristic. As the output potential of the discriminator-rectifier and hence the potential applied to the reactance tube 50 varies over the useful portion of the discriminator characteristic (the linear portion of the characteristic between the points A and B), the effect of the reactance tube is to shift the oscillator frequency in the same direction as the frequency changes which give rise to the demodulator potentials. If, on the other hand, we assume that a signal on the adjacent channel could reach the discriminator circuits and produce potentials caused by frequency variations over the side of the discriminator characteristic as indicated by the portion A-C of the curve, the phase of the potentials applied to the reactance tube would be such that the effect of the reactance tube on the oscillator would be to reverse the direction of the oscillator frequency change. That is, the reactance control tube cannot shift the oscillator frequency so that it will lock in with the signal on an adjacent channel because the circuit elements are so designed that if the frequency of the oscillator were to change beyond the useful range of the discriminator and towards the adjacent channel, the phase and magnitude of the potential applied to the reactance tube would shift in such a manner that the oscillation frequency would be shifted away from the adjacent channel frequencies. It will be noted further that the effect of the reactance tube on the frequency of the oscillator 12 for a signal at a frequency represented by the point C on the discriminator characteristic is just the same as

a signal of the same intensity at the frequency indicated by the point D. Thus, the reactance tube provides an additional restriction which limits the frequency variations of the lock-in oscillator to the range represented by the useful portion of the discriminator characteristic.

It is not essential that resistances 14' and 15', in shunt with circuits 14 and 15 respectively, be employed. They have, however, been found to be desirable to broaden the resonance curves of the circuits and to increase the linearity of the demodulator voltage-frequency response curve shown in Fig. 4. The values of these resistors 14' and 15' are not critical. In one embodiment of my invention they were 560,000 and 180,000 ohms respectively.

The ability of the oscillator to lock-in with a desired signal diminishes as the strength of the signal applied to the control grid drops below a certain value. This effect exhibits itself by a reduction in the lock-in range of the oscillator. From a practical standpoint the oscillator will lock in satisfactorily with any intermediate frequency signal which will produce a satisfactory audio output in a conventional receiver, assuming that the sensitivity or gain preceding the oscillator is comparable to that ahead of the limiter in the conventional frequency modulation receiver. However, it is possible to extend the lock-in range by having the effectiveness of the reactance tube control increase when very weak signals are being received. This is accomplished by having the effectiveness of the reactance tube controlled by the AVC potential. For this purpose control grid 52 may be means of switch contact member 75 be connected through contact 76 and resistors 78 and 78' to an adjustable contact 79 slidable along the resistor 39. The resistors 78 and 78' and grounded condenser 77 are used to filter out any alternating current potentials which may be set up across resistor 39.

Referring to Fig. 2 and assuming that the switch 70 is open circuited, and the contacts on switch 72 in shunt with the resistor 84 and condenser 83 in the cathode circuit of tube 50 are closed while contact arm 75 completes the circuit through contact 76, the AVC potential developed across resistor 39 is then applied to control grid 52 of the reactance tube to control its effectiveness. The oscillator may, if so desired, be designed to in itself have sufficient lock-in range for strong signals, but require the frequency control provided by the reactance tube to provide satisfactory lock-in for weak signals. This can be accomplished by using the AVC potential to provide the desired control of the effectiveness of the reactance tube.

On the other hand, it may be desirable to prevent the reactance tube from effecting a control of the oscillator frequency when it is not tuned to a desired modulated signal, as when the receiver is being tuned between stations. This can be accomplished by causing the plate current of one of the tubes, which is controlled by the AVC, to pass through the cathode resistor 84 of the reactance tube. Thus, when no modulated carrier signal is being received the amplifier plate current passing through resistor 84 increases the negative bias on the grid 52 of the reactance tube sufficiently to render it ineffective. When the receiver is tuned to a modulated carrier signal, the plate current is decreased, and the grid bias of the reactance tube then returns to a value where the reactance tube is effective in control-

ling the oscillator frequency. Such an arrangement is illustrated in Fig. 5 in which the cathode 80 of intermediate frequency amplifier 8 is connected to the upper end of resistance 84 so that the current between anode 82 and cathode 80 of one or more tubes in amplifier 8 also passes through resistance 84 in a direction to make the cathode of tube 50 positive with respect to ground. Inasmuch as the grid 52 of tube 50 is connected to ground either at 94 directly through resistance 73 or at 96 through a resistance network including A. V. C. resistor 39, a corresponding negative bias is impressed on grid 52 relative to its cathode in tube 50. Figs. 1 and 2 indicate that the intermediate frequency amplifier 8 is controlled by the AVC.

It will be seen that in the arrangement hereinabove described and illustrated in Fig. 5, resistance 84 provides negative grid bias both to the grid 52 of tube 50 and to the control grids of one or more tubes contained in I. F. amplifier 8. The resistance 84 is therefore preferably chosen to give normal bias as a cathode bias element for the intermediate frequency amplifier 8 in the absence of AVC action, while the reactance tube 50 is so constituted that the same voltage drop impressed as negative bias on the grid 52 renders the reactance tube 50 ineffective. This result may be effected in various ways known to the art, one of which involves the use of conventional screen grid amplifiers, of which pentodes would be one example, in intermediate frequency amplifier 8 and choosing the relation between the screen voltages of the I. F. amplifier 8 and the reactance tube 50 such that for the particular types of tubes employed, a bias sufficient to make the reactance tube 50 ineffective is of the correct value to provide normal amplification in the intermediate frequency amplifier. There are, of course, other circuit arrangements by which these results may be accomplished. If desired, additional selectivity may be included in the circuits controlling the effectiveness of the reactance tube.

As previously indicated, when the switch 70 is closed both the alternating and direct current components of the potential developed across resistor 55 are applied to the control grid of the reactance tube. When the switch 70 is open circuited only the alternating component is utilized. Under the latter condition, if AVC of the reactance tube is not desired the contact arm 75 is adjusted to complete the circuit through contact 14 and the resistor 73. The latter then completes the ground circuit for control grid 52.

It is, of course, obvious that in both the circuits shown in Figs. 1 and 2 the frequency swing can be reduced by ratios other than the 5:1 used in the examples previously described. It is likewise apparent that intermediate frequencies other than the 4.3 mc. can be used. An intermediate frequency up to 18 mc. may be used. An intermediate frequency such as 8.25 mc. might be used to provide greater lock-in range, if this is desired, since the percentage change in frequency is thereby reduced.

In the receiving system of this invention, as exemplified by both Figs. 1 and 2, the received signal as has been previously indicated does not pass through the receiving system to the discriminator in the conventional manner. The only effect of a received signal is to shift the frequency of the locked-in oscillator in accordance with the modulation, thereby causing the fre-

quency of the voltage applied to the discriminator to vary in accordance with the modulation of the received signal but with a reduced frequency swing. If oscillations are not produced by the oscillator 12 the system is inoperative to receive signals, inasmuch as energy at the intermediate frequency impressed on the grid 35 cannot pass through tube 12 and even if it could the selective circuits 14 and 15 designed to operate over ± 15 kc. could not respond to its frequency swing of ± 75 kc.

By the use of the circuits described above, satisfactory "lock-in" of the oscillator has been obtained with a signal potential applied to control grid 35 of approximately one volt and with a potential of at least 15 volts applied to the discriminator from the oscillator. It will be noted that this voltage gain is obtained at a frequency which differs from either that of the radio frequency or intermediate frequency circuits, and therefore contributes materially to the overall stability of the receiver as previously discussed. Since one of the major problems in frequency modulation receivers is to obtain high sensitivity or gain with stability, and since the gain which can be obtained with reasonable precautions at any specific frequency is definitely limited, the additional gain obtained at a considerably lower frequency is important. Another advantage of the receiving system which has been described is that because the discriminator operates at a much lower frequency than in conventional receivers, the circuit constants can be more readily controlled since the frequency band over which the circuits operate is correspondingly reduced. A third, and likewise important, advantage of the invention lies in the improved adjacent channel selectivity obtained. In a conventional frequency modulation receiver, the adjacent channel selectivity is determined by the response curves of the radio frequency, intermediate frequency and discriminator circuits. If the signal on the channel adjacent to a desired signal is sufficiently strong to produce a voltage of a certain value at the discriminator-rectifier network, interference with the desired signal will be obtained even though the frequency deviations of the undesired signal do not operate over the useful portion of the discriminator characteristic. In the receiver of this invention the only signal which reaches the discriminator is represented by the frequency variations in the voltages produced by the locked-in oscillator. By limiting the "lock-in" range of the oscillator to the useful band width of the discriminator characteristic, the selectivity of the receiver is materially increased without resorting to the use of additional selective circuits.

Two embodiments of a frequency modulation receiving system have been described in which the frequency swing of a received signal is reduced with a corresponding reduction in the modulation index, or effective percentage modulation, before the signal is converted into amplitude variations in the frequency selective network or discriminator. Interfering frequencies which would differ from the carrier wave by a frequency above audibility are substantially prevented from combining with the carrier wave in the demodulator since the discriminator circuits are responsive only to a narrow frequency band. Thus the ratio of the signal to side band energy is materially increased.

The arrangement of Fig. 2 has been found to be particularly effective in separating desired signal frequencies from interfering frequencies result-

ing either from noise impulses or adjacent channel signals. Good reception has been achieved despite low signal to noise ratio, even with weak signals.

5 Automatic frequency control of the heterodyne oscillator 1 may be employed to improve the tuning of the receiver and to compensate for frequency drift of the oscillator 1. To this end the potentials developed across resistor 18 in Fig. 1 or resistor 18 and potentiometer 55 of Fig. 2 may control a reactance tube associated with the oscillator 1, as fully shown in the prior art including United States patents to G. L. Beers, No. 2,203,857, granted June 11, 1940, and to S. W. Seeley, No. 2,121,103, granted June 21, 1938.

10 Also inter-station noise suppression systems, such as the types described in United States patents to G. L. Beers, No. 2,135,557, granted Nov. 8, 1938; Jarvis, No. 2,115,813, granted May 3, 1938, 20 Starrett No. 1,925,825, granted Sept. 5, 1933, can be used in conjunction with this receiving system. Since the locked-in oscillator 12 can be started and stopped by control of the potentials applied to grids 35 and 44 and noise suppression potentials derived as described in the above mentioned 25 patents may be applied to grid 35 or grid 44 or both, a simple means is provided for giving such noise suppression systems an ON/OFF characteristic which cannot be obtained in a similar manner in conventional receivers.

30 While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

40 1. In a frequency modulation receiving system, a circuit for receiving frequency modulated waves, means for supplying frequency modulated signal waves to said circuit, a demodulator, selective circuits in the input of the demodulator for converting frequency variations to amplitude variations, and connections between said receiving circuit and said selective circuits, said connections including means for increasing the selectivity of the system and said last-named means including 45 oscillation producing means locked in step with a desired frequency modulated wave over a range of frequency variations including, and substantially limited to, the range of frequencies of the desired modulated waves, whereby interference due to noise frequencies or adjacent channel frequencies is reduced.

50 2. In a frequency modulation receiving system, a circuit for receiving frequency modulated waves, means for supplying frequency modulated signal waves to said circuit, a demodulator, selective 55 circuits in the input of the demodulator for converting frequency variations to amplitude variations, and means connected between said receiving circuit and said selective circuits for improving the signal to noise ratio of the system, said last-named means including an oscillator, means for coupling the output of the oscillator to said selective circuits, and means including said coupling means for causing said oscillator to lock in with a desired frequency modulated wave over a range of frequency variations including, and substantially limited to, the range of frequencies of the desired modulated wave.

60 3. In a frequency modulation receiving system, 65 a circuit for receiving frequency modulated waves,

means for supplying frequency modulated signal waves to said circuit, a demodulator, oscillation producing means connected between said receiving circuit and the demodulator for improving the signal to noise ratio of the system, means for coupling the output of the oscillation producing means to the demodulator, means including said coupling means for causing said oscillator to lock in with a desired frequency modulated wave over a range of frequency variations including, and substantially limited to, the range of frequencies of the modulated wave, and means for varying the degree of coupling between the oscillator and the demodulator to control the width of the frequency range over which the oscillation producing means will lock in with the desired modulated wave supplied to said receiving circuit.

4. In a frequency modulation receiving system, a circuit for receiving frequency modulated waves, means for supplying frequency modulated signal waves to said circuit, a demodulator, selective circuits in the input of the demodulator for converting frequency variations to amplitude variations, an oscillator having a tank circuit containing inductance and capacity and having its output coupled to said selective circuits, and means including the inductance-capacity ratio of the oscillator tank circuit and the degree of coupling between the oscillator and said selective circuits for causing the oscillator to lock in with a desired frequency modulated wave over a range of frequency variations substantially restricted to the range of frequencies of such modulated wave, so as not to respond to undesired noise or adjacent channel frequencies.

5. In a frequency modulation receiving system, a circuit for receiving frequency modulated waves, means for supplying frequency modulated signal waves to said circuit, a demodulator, selective circuits in the input of the demodulator for converting frequency variations to amplitude variations, a vacuum tube containing an anode, cathode and a plurality of grids, means for impressing frequency modulated signal waves from said receiving circuit on one of said grids, an oscillator including said anode, another of said grids, and a tank circuit containing inductance and capacity and having its output coupled to said selective circuits, and means including the inductance-capacity ratio of the oscillator tank circuit and the degree of coupling between the oscillator and said selective circuits for causing the oscillator to lock in with a desired frequency modulated wave over a range including, and substantially limited to, the range of frequencies of such modulated wave.

6. In a frequency modulation receiving system, a circuit for receiving frequency modulated waves, means for supplying frequency modulated signal waves to said circuit, a demodulator, a vacuum tube containing an anode, cathode and a plurality of grids, means for impressing frequency modulated signal waves from said receiving circuit on one of said grids, an oscillator having its output coupled to said selective circuits and including said anode, another of said grids, a tank circuit connected to the anode and containing inductance and capacity, and a resistance shunted by a capacity in the circuit of said other grid together with parallel-resonant inductance and capacity resonating at a frequency higher than that of the tank circuit, and means including the inductance-capacity ratio of the oscillator tank circuit and the degree of coupling between the oscillator and said selective circuits for caus-

ing the oscillator to lock in with a desired frequency modulated wave over a range of frequency variations substantially restricted to the range of frequencies of such modulated wave, so as not to respond to undesired noise or adjacent channel frequencies.

7. In a frequency modulated carrier wave receiving system, a receiving circuit, means for supplying to said circuit waves modulated over a range of frequencies, a demodulator having an input network responsive to frequencies which are sub-multiples of the first-mentioned frequencies and having a pass band of a width bearing substantially the same ratio to the width of said first-mentioned range of frequencies as said sub-multiple frequencies bear to the first-mentioned frequencies, oscillation producing means interposed between the receiving circuit and said demodulator input network, said oscillation producing means impressing voltages on the demodulator input network at frequencies of operation of the oscillation producing means and which are sub-multiples of the first-mentioned frequencies and which vary over a correspondingly reduced frequency range, and means for causing the oscillation producing means to lock in with a desired frequency modulated wave over a range including, and substantially limited to, the range of frequencies of such modulated wave.

8. In a frequency modulated carrier wave receiving system, a receiving circuit, means for supplying to said circuit signal waves modulated over a range of frequencies, a demodulator having an input network responsive to frequencies which are sub-multiples of the first-mentioned frequencies and having a pass band of a width bearing substantially the same ratio to the width of said first-mentioned range of frequencies as said sub-multiple frequencies bear to the first-mentioned frequencies, a vacuum tube oscillator interposed between the receiving circuit and said demodulator input network, said oscillator having an input circuit tuned to receive signals over the first-mentioned range of frequencies and producing voltages at frequencies which are sub-multiples of the first-mentioned frequencies and which vary in frequency over a correspondingly reduced frequency range, and means including coupling elements between the output of the oscillator and the demodulator input network for causing the oscillator to lock in with a desired frequency modulated wave over a range including, and substantially limited to, the range of frequencies of the modulated wave.

9. In a frequency modulation receiving system, a circuit for receiving frequency modulated waves, means for supplying frequency modulated signal waves to said circuit, a demodulator, selective circuits in the input of the demodulator for converting frequency variations to amplitude variations and responsive to sub-multiples of the frequency modulated waves, a vacuum tube oscillator, devices including resistance and capacity for coupling the output of the oscillator to said selective circuits, and means including said coupling devices for causing the oscillator to deliver to said selective circuits voltages at frequencies directly produced by said oscillator and which are sub-multiples of the frequencies of a desired frequency modulated wave supplied to said receiving circuit over a range of frequency variations substantially restricted to the frequencies of said wave.

10. In a frequency modulation receiving system, a circuit for receiving frequency modulated

waves, means for supplying frequency modulated signal waves to said circuit, said means including vacuum tube devices for increasing the strength of the modulated waves, a demodulator having an input network responsive to sub-multiples of the frequency modulated waves, a vacuum tube oscillator, including a control grid and a plurality of oscillation-producing electrodes for supplying voltages of said sub-multiple frequencies to the demodulator, and means energized by flow of current in the circuit of said control grid for automatically controlling the gain of said vacuum tube devices.

11. In a frequency modulation receiving system, the combination of a circuit supplying signal waves modulated over a range of frequencies, a demodulator having an input network responsive to the fifth sub-multiple frequencies of the range of frequencies of said applied waves and having a pass band of a frequency width approximately equal to one-fifth of the width of said range of frequencies, frequency division means interposed between said supply circuit and said demodulator input network and controlled by the signal waves over said range of frequencies, said frequency division means being constructed to reduce said supplied frequencies to said sub-multiple frequencies and to reduce said range of frequencies to the narrower range to which said input network is responsive, and circuits associated with the frequency division means for limiting its control substantially to the range of frequencies of a desired wave.

12. In a frequency modulation receiving system, the combination of a circuit supplying signal waves modulated over a range of frequencies including frequencies having superaudible frequency differences from the mean frequency of said range of frequencies, a demodulator having an input network responsive to sub-multiple frequencies of the range of frequencies of said applied waves and having a pass band of a frequency width within the limits of audibility on each side of the mean frequency, and bearing approximately the same ratio to the width of said range of frequencies as said sub-multiple frequencies bear to said first-mentioned frequencies, an oscillator interposed between said supply circuit and said demodulator input network and controlled by a desired signal wave over the range of frequencies of said wave, said oscillator being constructed to produce oscillations of the range of frequencies to which said demodulator input network is responsive and to reduce said supplied frequencies to said sub-multiple frequencies and to reduce the range of frequencies of a desired signal wave to the narrower range to which said input network is responsive, and circuits associated with the oscillator for limiting its control substantially to the range of frequencies of the desired signal wave.

13. In a frequency modulation receiving system, a receiving circuit for waves modulated over a range of frequencies, means for reproducing the received signals, and means for discriminating in favor of a desired signal and against interfering noise and undesired signals, comprising oscillation producing means constructed for control by incoming potentials only over the frequency swing of the desired signal.

14. In a frequency modulation receiving system, a receiving circuit for waves modulated over a range of frequencies, means for reproducing the received signals and means for discriminating

in favor of a desired signal and against interfering noise and undesired signals comprising a circuit responsive over a range of frequencies substantially less than said first-mentioned range and oscillation producing means controllable by incoming potentials only over the range of frequencies of a desired modulated wave and operating to produce in the output of the oscillation producing means voltages at frequencies to which 10 said second-mentioned circuit is responsive and which are sub-multiples of the frequencies within in the first-mentioned range.

15. In a frequency modulation receiving system, a circuit for receiving waves over a range of frequencies corresponding to full modulation, a demodulator responsive to a frequency swing substantially less than said range of frequencies and means interposed in direct path between said circuit and said demodulator for reducing the 20 range of frequencies of signals applied to said circuit to the narrower frequency swing to which the demodulator is responsive, said means including a vacuum tube oscillator including an anode, a cathode, a plurality of other electrodes, 25 and at least one tuned circuit connected with certain of said electrodes to determine the approximate frequency of operation of said oscillator, and input signal means connected to an electrode of said tube other than said certain electrodes for varying the frequency of said oscillator within a range limited by constants of said tuned circuit or circuits.

16. In a frequency modulation receiving system, a circuit for receiving waves over a range of 35 frequencies corresponding to full modulation, a demodulator including a reactance network responsive to a frequency swing substantially less than said range of frequencies and means interposed in direct path between said circuit and said demodulator for reducing the range of frequencies of signals applied to said circuit to the narrower frequency swing to which the demodulator is responsive, said means including a vacuum tube oscillator including an anode, a cathode, a plurality of other electrodes, and a second 45 reactance network including at least one tuned circuit connected with certain of said electrodes to determine the approximate frequency of operation of said oscillator, and input signal means connected to an electrode of said tube other than said certain electrodes for varying the frequency of said oscillator within a range limited by the constants of said second network.

17. In a frequency modulation receiving system, a circuit for receiving waves modulated over a range of frequencies, means for reproducing the received signals, and interference preventing devices comprising oscillation producing means constructed and arranged to lock in with a desired modulated wave over a range of frequencies less than that of such modulated wave, and means additional to said aforesaid means for extending the lock-in range of the oscillation producing means to include the whole of the range of frequencies of the desired modulated wave.

18. In a frequency modulation receiving system, a circuit for receiving waves modulated over a range of frequencies, means for reproducing the received signals, and means for increasing the signal to noise ratio of the system comprising oscillation producing means constructed in and of itself to lock in with the frequencies of a desired modulated wave over a portion only 70 of its range of frequencies, and additional means 75 of the system for receiving waves modulated over a portion of its range of frequencies and for combining the signals of the system with the signals of the additional means.

responsive automatically to changes in frequency of the modulated wave for causing said oscillation producing means to lock in with it over the whole of its range of frequencies.

19. In a frequency modulation receiving system, a demodulator, means inherently responsive to only small frequency variations in a received signal for supplying to the demodulator energy modulated in accordance with the signal, means controlled by the modulation of received signals for shifting in frequency the narrow response range of said first named means including the mean frequency of said range so that wide frequency variations in received signals can be accommodated, and means for rendering the frequency shifting means normally ineffective in the absence of received signals.

20. In a frequency modulation receiving system, a circuit for receiving waves modulated over a range of frequencies, means including a demodulator for reproducing the desired signals, and interference preventing devices comprising oscillation producing means which, in the absence of other provisions, locks in with a desired modulated wave over a portion only of its range of frequencies, and additional means controlled by voltages produced in the output of the demodulator for extending the lock-in range of said oscillation producing means sufficiently to include the whole of the range of frequencies of the desired modulated wave but not enough to include frequencies substantially outside of said last-mentioned range.

21. In a frequency modulation receiving system, a circuit for receiving waves modulated over a range of frequencies, means for reproducing the desired signals comprising a demodulator, and means for discriminating in favor of desired signals as against interfering frequencies, comprising a vacuum tube oscillator having a tank circuit and operating, in the absence of other provisions, to lock in with a desired modulated wave over a portion only of its range of frequencies, a reactance tube connected across the tank circuit, and means for impressing voltages from the output of the demodulator on the reactance tube to change the tuning of the tank circuit in the direction of frequency change of the desired modulated wave.

22. In a frequency modulation receiving system, a circuit for receiving waves modulated over a range of frequencies, means for reproducing the desired signals comprising a demodulator having an input network responsive to frequencies which are submultiples of the range of frequencies of the modulated waves and having a pass band of a width bearing approximately the same ratio to the width of said range of frequencies as the submultiple frequencies bear to the frequencies in said receiving circuit, oscillation producing means connected between said receiving circuit and the demodulator input network and constructed to lock in with a desired modulated wave over a portion only of its range of frequencies to produce in the output of the oscillation producing means voltages at sub-multiple frequencies of the modulated wave, and means operating automatically in response to a desired modulated wave for causing the oscillation-producing means to produce voltages at sub-multiples of the frequencies of such modulated wave over the whole of its range of frequencies.

23. In a frequency modulation receiving system, a circuit for receiving waves modulated over

75 a range of frequencies, means for reproducing the desired signals, and interference preventing means comprising a vacuum tube oscillator having an input circuit which receives signals from said receiving circuit and an output circuit which feeds alternating current to said signal reproducing means and having a tank circuit which, in the main, controls the frequencies of the voltages produced by the oscillator, said oscillator being constructed to lock in with a desired modulated wave on each side of the tank circuit frequency and over a portion only of the range of frequencies of the desired wave, and means under the control of a desired modulated wave for automatically varying the frequency of the tank circuit in the direction of frequency change of the modulated wave so as to enable the vacuum tube oscillator to lock in with it over the whole of its range of frequencies.

24. In a frequency modulation receiving system, a circuit for receiving waves modulated over a range of frequencies, means for reproducing the desired signals comprising a demodulator having an input network responsive to sub-multiples of said range of frequencies, and means for discriminating in favor of desired signals as against interfering frequencies comprising a vacuum tube oscillator constructed to produce voltages of said sub-multiple frequencies and operating inherently to lock in with a desired modulated wave over a portion only of its range of frequencies, said vacuum tube oscillator having a tank circuit, a reactance tube connected across the tank circuit, means for impressing voltages from the output of the demodulator on the reactance tube to change the tuning of the tank circuit in the direction of frequency change of the desired modulated wave, and automatic volume control means for controlling the effectiveness of the reactance tube in changing the frequency of the oscillator.

25. In a frequency modulation receiving system, a demodulator, means inherently responsive to only small frequency variations in a received signal for supplying to the demodulator energy modulated in accordance with the signal, means for shifting in frequency the narrow response range of said first named means so that wide frequency variations in the received signal can be accommodated, means for making the frequency shifting means normally ineffective in the absence of received signals, and means for rendering the frequency shifting means operative under the control of received signals.

26. In a frequency modulation receiving system, a receiving circuit responsive to a desired signal and to interfering frequencies which can beat either with themselves or the received signal to produce superaudible noise impulses, a demodulator, means inherently responsive to only small frequency variations in the received signal for supplying frequency modulated energy to the demodulator, and means for shifting in frequency the narrow response range of said first named means including the mean frequency of said range so that wide frequency variations in the received signal can be accommodated, said last-named means including circuits controlled by the modulation of the received signal and unresponsive to said superaudible noise impulses.

27. A frequency modulation receiving system comprising means including a demodulator for reproducing the audio frequency modulations of received signals, and means for limiting the range of frequencies to which the receiver is respon-

sive, said means comprising oscillation producing means, and means controlled by the demodulator for changing the frequency of the oscillations produced by the oscillation producing means in the direction of changes in the frequency of a desired modulated wave and at a rate corresponding with and substantially restricted to the audio frequency modulation of the wave, whereby interference from frequencies varying at a rate above audibility is suppressed.

28. In a frequency modulating system, a circuit for receiving modulated waves, means for reproducing the desired signals comprising a demodulator which produces a voltage varying substantially linearly with frequency over a range of frequencies necessary for reception of full modulation, a frequency division network connected between the receiving circuit and the demodulator for supplying to the demodulator sub-multiple frequencies of said first-mentioned range of frequencies, and means controlled by the demodulator for preventing the division network from supplying to the demodulator frequencies substantially outside of the range required for full modulation reception.

29. In a frequency modulation receiving system, a circuit for receiving waves modulated over a range of frequencies, means for reproducing the received signals including a demodulator constructed to produce voltages varying substantially linearly with frequency over a band of frequencies which enables reception of said range of frequencies, and interference preventing means comprising a vacuum tube oscillator having a tank circuit, a reactance tube connected across the tank circuit, and circuits for impressing output potentials from the demodulator on the reactance tube to cause said tube to vary the frequency of the oscillator in the direction of the frequency changes of a desired modulated wave over a desired operating range, said last-mentioned circuits being so constructed as not to pass demodulator output potentials of frequencies outside of the desired modulation frequency band.

30. In a frequency modulation receiving system, a circuit for receiving frequency modulated waves, means for supplying frequency modulated signal waves to said circuit, a demodulator, selective circuits in the input of the demodulator for converting frequency variations to amplitude variations, and connections between said receiving circuit and said selective circuits, said connections including tuned circuit means and thermionic means connected in cascade with the tuned circuit means for materially increasing the selectivity of the receiving system without altering the selectivity of the tuned circuit means, said thermionic means operating to produce oscillations locked in step with a desired frequency modulated wave over a range of frequency variations including, and substantially limited to, the range of frequencies of the desired modulated waves, whereby interference due to noise frequencies or adjacent channel frequencies is reduced.

31. In a frequency modulation communication system, a circuit responsive over a range of frequencies of a frequency modulated wave, a second circuit responsive to a frequency swing substantially less than said range of frequencies, means interposed in direct path between said first circuit and said second circuit for reducing the range of frequencies of signals applied to said circuit to the narrower frequency swing to which the second circuit is responsive, said means including a vacuum tube oscillator including an anode, a

cathode, a plurality of other electrodes, and at least one tuned circuit operatively connected with certain of said electrodes to determine the approximate frequency of operation of said oscillator, and input signal means connected to an electrode of said tube other than said certain electrodes for varying the frequency of said oscillator within a range limited by constants of said tuned circuit or circuits.

10 32. In a frequency modulation communication system, a source of high frequency carrier energy which is frequency modulated over a range of frequencies, a circuit responsive to a frequency lower than said first-mentioned carrier frequency and to a frequency swing substantially less than said range of frequencies, and means interposed in direct path between said source and said circuit for dividing the carrier frequency to reduce it to the frequency of said circuit and for reducing the 15 range of frequencies of energy supplied to said circuit to the narrower frequency swing to which the circuit is responsive, said means including a vacuum tube oscillator including an anode, a cathode, a plurality of grid electrodes, and at least one tuned circuit operatively connected with said anode and one of said grid electrodes to determine the approximate frequency of operation of said oscillator, input signal means connected to a grid electrode of said tube nearer the 20 cathode than said first-mentioned grid electrode for varying the frequency of said oscillator within a range limited by constants of said tuned circuit or circuits, and a screen electrode interposed between said first-mentioned grid electrodes.

25 33. In frequency modulation signalling apparatus, a tuned circuit having a substantially flat response over a range of frequencies of a frequency modulated wave, said circuit being tuned to substantially the mid-frequency of the range, a second circuit having a flat response over a band substantially less than the said range of frequencies, said second circuit consisting of a coil and a condenser connected in parallel and tuned to a submultiple of the frequency to which 30 the first circuit is tuned, a vacuum tube having an anode, a cathode, a control grid adjacent the cathode, a suppressor grid adjacent the anode, an intermediate grid and a shielding grid adjacent the intermediate grid, said second circuit being connected to and between said anode and cathode of said tube, an inductance coil coupled to the coil of said second circuit and connected to and between said intermediate grid and said cathode, means for developing and subjecting said 35 intermediate grid to a negative potential with respect to said cathode, whereby said second circuit and the coil coupled thereto regeneratively set up oscillations of submultiple frequency in said second tuned circuit, means connecting the suppressor grid directly to the cathode, means subjecting the shielding grid to a positive potential with respect to said cathode, a resistance connected between the control grid and said cathode for subjecting said control grid to a negative potential with respect to said cathode, a circuit 40 coupling said first tuned circuit to said control grid, whereby frequency modulated waves fed to said first tuned circuit cause the oscillations regeneratively set up in said second tuned circuit to vary in exact submultiple proportion with the frequency modulated wave, and means for utilizing the frequency modulated waves of reduced frequency range so set up.

45 46. In a frequency modulation communication system, a source of high frequency carrier energy which is frequency modulated over a range of frequencies, a circuit responsive to a frequency lower than said first-mentioned carrier frequency and to a frequency swing substantially less than said range of frequencies, and means interposed in direct path between said source and said circuit for dividing the carrier frequency to reduce it to the frequency of said circuit and for reducing the 50 range of frequencies of energy supplied to said circuit to the narrower frequency swing to which the circuit is responsive, said means including a vacuum tube oscillator including an anode, a cathode, a plurality of grid electrodes, and at least one tuned circuit operatively connected with said anode and one of said grid electrodes to determine the approximate frequency of operation of said oscillator, input signal means connected to a grid electrode of said tube nearer the cathode than said first-mentioned grid electrode for varying the frequency of said oscillator within a range limited by constants of said tuned circuit or circuits, and a screen electrode interposed between said first-mentioned grid electrodes.

55 56. In frequency modulation signalling apparatus, a tuned circuit having a substantially flat response over a range of frequencies of a frequency modulated wave, said circuit being tuned to substantially the mid-frequency of the range, a second circuit having a flat response over a band substantially less than the said range of frequencies, said second circuit consisting of a coil and a condenser connected in parallel and tuned to a submultiple of the frequency to which the first circuit is tuned, a vacuum tube having an anode, a cathode, a control grid adjacent the cathode, a suppressor grid adjacent the anode, an intermediate grid and a shielding grid adjacent the intermediate grid, said second circuit being connected to and between said anode and cathode of said tube, an inductance coil coupled to the coil of said second circuit and connected to and between said intermediate grid and said cathode, means for developing and subjecting said intermediate grid to a negative potential with respect to said cathode, whereby said second circuit and the coil coupled thereto regeneratively set up oscillations of submultiple frequency in said second tuned circuit, means connecting the suppressor grid directly to the cathode, means subjecting the shielding grid to a positive potential with respect to said cathode, a resistance connected between the control grid and said cathode for subjecting said control grid to a negative potential with respect to said cathode, a circuit coupling said first tuned circuit to said control grid, whereby frequency modulated waves fed to said first tuned circuit cause the oscillations regeneratively set up in said second tuned circuit to vary in exact submultiple proportion with the frequency modulated wave, and means for utilizing the frequency modulated waves of reduced frequency range so set up.

60 61. In a frequency modulation communication system, a source of high frequency carrier energy which is frequency modulated over a range of frequencies, a circuit responsive to a frequency lower than said first-mentioned carrier frequency and to a frequency swing substantially less than said range of frequencies, and means interposed in direct path between said source and said circuit for dividing the carrier frequency to reduce it to the frequency of said circuit and for reducing the range of frequencies of energy supplied to said circuit to the narrower frequency swing to which the circuit is responsive, said means including a vacuum tube oscillator including an anode, a cathode, a plurality of grid electrodes, and at least one tuned circuit operatively connected with said anode and one of said grid electrodes to determine the approximate frequency of operation of said oscillator, input signal means connected to a grid electrode of said tube nearer the cathode than said first-mentioned grid electrode for varying the frequency of said oscillator within a range limited by constants of said tuned circuit or circuits, and a screen electrode interposed between said first-mentioned grid electrodes.

65 66. In frequency modulation signalling apparatus, a tuned circuit having a substantially flat response over a range of frequencies of a frequency modulated wave, said circuit being tuned to substantially the mid-frequency of the range, a second circuit having a flat response over a band substantially less than the said range of frequencies, said second circuit consisting of a coil and a condenser connected in parallel and tuned to a submultiple of the frequency to which the first circuit is tuned, a vacuum tube having an anode, a cathode, a control grid adjacent the cathode, a suppressor grid adjacent the anode, an intermediate grid and a shielding grid adjacent the intermediate grid, said second circuit being connected to and between said anode and cathode of said tube, an inductance coil coupled to the coil of said second circuit and connected to and between said intermediate grid and said cathode, means for developing and subjecting said intermediate grid to a negative potential with respect to said cathode, whereby said second circuit and the coil coupled thereto regeneratively set up oscillations of submultiple frequency in said second tuned circuit, means connecting the suppressor grid directly to the cathode, means subjecting the shielding grid to a positive potential with respect to said cathode, a resistance connected between the control grid and said cathode for subjecting said control grid to a negative potential with respect to said cathode, a circuit coupling said first tuned circuit to said control grid, whereby frequency modulated waves fed to said first tuned circuit cause the oscillations regeneratively set up in said second tuned circuit to vary in exact submultiple proportion with the frequency modulated wave, and means for utilizing the frequency modulated waves of reduced frequency range so set up.

70 71. In a frequency modulation communication system, a source of high frequency carrier energy which is frequency modulated over a range of frequencies, a circuit responsive to a frequency lower than said first-mentioned carrier frequency and to a frequency swing substantially less than said range of frequencies, and means interposed in direct path between said source and said circuit for dividing the carrier frequency to reduce it to the frequency of said circuit and for reducing the range of frequencies of energy supplied to said circuit to the narrower frequency swing to which the circuit is responsive, said means including a vacuum tube oscillator including an anode, a cathode, a plurality of grid electrodes, and at least one tuned circuit operatively connected with said anode and one of said grid electrodes to determine the approximate frequency of operation of said oscillator, input signal means connected to a grid electrode of said tube nearer the cathode than said first-mentioned grid electrode for varying the frequency of said oscillator within a range limited by constants of said tuned circuit or circuits, and a screen electrode interposed between said first-mentioned grid electrodes.
